DOOR HOLDER

Herman J. Troche, Fairview Park, Ohio, assignor to J. H. Holan Corporation, Cleveland, Ohio, a corporation of Ohio

Application May 17, 1952, Serial No. 288,377

7 Claims. (Cl. 16—85)

The invention relates to door holders. Particularly, it relates to devices for securely holding doors open, and is illustrated herein by a description and a showing thereof when applied to a door of a utility truck body. Such vehicle bodies are utilized for transporting the workmen and the equipment necessary for the installation and maintenance of power lines, telephone lines, and other facilities of public utility companies.

The invention utilizes various body and door parts, either in their usual form, or slightly modified, and incorporates these parts with additional elements to form the door holder and to effect the door-holding function.

The objects of the invention are to provide a door holder which is economically manufactured, and can be conveniently installed in equipment of the character described; which is entirely automatic in operation upon movement of the door; which forms no impediment to the normal use of the door; and which is entirely reliable in that it is practically impossible for the door to be closed accidentally when locked open by the holder.

The annexed drawings and the following description set forth in detail certain means illustrating the improvements in door holders; the same, however, disclosing only one of the various forms in which the principle of the invention may be embodied:

In said annexed drawings:

Figure 1 is an outside elevation of a utility body door with which the improvements in door holders have been incorporated, a fragmentary showing of a truck body served by the door being also included; the door in this view being shown in closed position;

Figure 2 is a plan section, upon an enlarged scale, taken in the planes indicated by the line 2—2, Figure 1;

Figure 3 is a transverse vertical section, looking toward the rear of the truck body, the view being taken in the plane indicated by the line 3—3, Figures 1 and 5;

Figure 4 is a broken plan view, similar to Figure 2, the door, however, being shown in fully open and locked position, certain parts of the door and door-locking members being also indicated in the respective positions which they occupy in the closed position of the door;

Figure 5 is a fragmentary longitudinal, vertical section, looking from within the truck body toward the door, the section being taken in the plane indicated by the line 5—5, Figures 2 and 3; and

Figure 6 is a section taken in the plane indicated by the line 6—6, Figure 4.

Referring to the annexed drawings in which the same parts are indicated by the same several numbers in the respective views, a utility truck body 1 is formed with an opening 2, Figure 2, for the accommodation of a closure, such as the door 10, Figure 1. The door 10 is illustrated in the accompanying drawings as swinging on a vertical axis and is assumed to be on the right or curb side of the body 1. Lapped by the edges of the door 10 are a relatively front body part 3, Figure 1, a relatively rear body part 4, an upper body part 5, and a lower body part 6. The upper body part 5 also includes a roof 7 lapped by the upper edge of the door.

The form of door shown is the box type having transversely-spaced rectangular panels; an outer one 11 and an inner one 15, Figure 3, of which portions are shown at the upper and lower door corners at the hinge edge of the door, Figures 2 and 4. The two panels 11 and 15 are spaced one from the other by a peripheral substantially right-angular flange 16 of the interior panel 15, Figures 2 and 3, which flange 16 is welded by a

2

right-angular edge 17 to the peripheral portion of the inner face of the outer panel 11. The terminal edges of the outer panel 11 are folded over into a two-ply formation 11' upon all sides except the hinge side, Figures 2 and 4, and the terminal edges 17 of the flange 16 of the inner panel 15 abut the inner edges of the formation 11'.

Certain body and door structures shown in the accompanying drawings, particularly at the hinge edge of the door, are similar to structures shown, described, and claimed in the pending application of Herman J. Troche and James Howard Holan, on Sealing Means for the Hinge Edge of a Door, Serial No. 5,244, now Patent No. 2,619,204, dated November 25, 1952, and are as follows:

The outer panel 11 extends at the forward or hinge edge of the door 10 forwardly of the inner panel flange 17 and has an elongated forwardly-extended inwardly-bent terminal edge 14 which is biased outwardly and which, when the door 10 is closed, abuts the inner face of the forward body part 3, as clearly appears in Figures 2 and 4. For the purpose of providing this inner lapping edge 14, the panel 11 is bent into an inwardly extended offset formation 13 adjacently forward of the inner panel flange 17, Figures 2 and 4. The offset 13 is disposed somewhat rearwardly of the rear edge of the forward body part 3 so as to form an opening 12, Figure 4, therebetween. The forwardly extending edge of the outer door panel 11 is cut away at its upper and lower corners, as indicated by 19, Figure 1, so that the part of the outer panel 11 adjacently rearwardly of the lapping edge 14 can move inwardly when the door 10 is opened, the opening 12 facilitating this movement.

Secured to the lower body part 6 and to the upper body part 5 adjacent the hinge edge of the door 10 are horizontal brackets 25 formed with relatively right-angular bushing members 26 within which projecting ends of upper and lower vertical hinge pins 8 and 9 secured to the door 10 are pivotally mounted. These brackets 25 are positioned in reversed positions so as to receive an upwardly extending end of the upper hinge pin 8 and a downwardly extending end of the lower hinge pin 9.

Means for manually opening and closing the door 10 comprise a cup or liner 20 seated at its base on the outer face of the inner door panel 15, in a recessed part of the outer door panel 11, of which liner 20 a flange 21 is shown in Figure 1 which is secured in close abutting position to the outside face of the outer door panel 11 adjacent the rear edge of the door 10, the chamber of this cup or liner 20 receiving lock-bolt operating structure (not shown) which is actuated from outside of the door 10 by pulling outwardly on the front edge of a handgrip 22 pivotally mounted in the liner 20.

Incorporated with the aforescribed body and door structures are the following elements:

Welded to the face of the inner door panel 15, on the hinge side of the door, is a strengthening member 27 having an outwardly directed flange 28 welded to the top face of the inner door panel flange 16. The strengthening member 27 extends at its forward end to substantially the plane of the forward edge of the terminal flange 17 of the inner door panel 15, and is bent forwardly right-angularly at its bottom edge to form a channel-shaped bracket 29 to and within which the upper hinge pin 8 is secured and extends upwardly therefrom for pivotally mounted movement in the upper bracket 25.

There is a lower strengthening member 31, similar in formation but of materially less longitudinal dimension than the upper strengthening member 27, which also is secured to the inner door panel 15. This lower strengthening member 31 is utilized in a reversed position from that in which the upper strengthening member 27 is utilized. The lower strengthening member 31 has a flange 32 secured to the lower face of the flange 16 of the inner door panel 15. This lower strengthening member 31 has a channel bracket formation 33 within and to which the lower hinge pin 9 is secured.

Material of the upper strengthening member 27 is stamped out, Figure 4, and is bent substantially 90° to form a bracket 23, which is a substantially triangular ear-shaped inwardly-extending member, the resultant re-

cess in the strengthening member 27 being indicated by 24. The ear 23 is drilled to receive a bolt 36, Figures 3 and 5, by which the forward end of a rearwardly extending metal arm 35 of elongated plate or strip formation, and substantially rectangular in cross section, is pivotally secured to the ear 23.

The strip 35 has at its rear terminal end a downwardly extending hook formation 39, Figures 5 and 6. The rear end portion of the strip 35 slopes downwardly as indicated by 37, and then is bent sharply upwardly, and thence into the downwardly-extending hook formation 39, a notch thus formed immediately forward of the hook formation, and on the top of the strip portion 37, being indicated by 38, Figures 5 and 6.

Spot-welded to the upper surface of the forward part of the strip 35 is a spring steel heat-treated rectilinear strip 40, also substantially rectangular in cross-section and extending rearwardly to substantially the plane defining the rear end of the hook formation 39, as clearly shown in Figures 5 and 6. These strips 39 and 40 extend lengthwise of the body 1 adjacently below the lower face of the roof 7. The spring steel strip 40 extends substantially in a horizontal plane so that the free ends of the strips 35 and 40 diverge and there is a space 41 continuously varying in vertical dimension between the top face of the rear of the strip 35 and the bottom face of the rear of the spring steel strip 40, as also clearly indicated in Figure 5. Preferably, the terminal portion 44 of the free end of the spring steel strip 40 is curved upwardly slightly, as seen in Figure 5.

Secured by one leg 46 to the undersurface of the body 7, at substantially a 45° angle to the plane of the door 10 in closed position, is a bracket such as an angle plate 45, Figures 2, 3, 4, 5 and 6. A depending leg 47 of the angle plate 45 is formed with a slot 42 through which pass the rear ends of the metal strip 35 and the spring steel strip 40. The rear parts of these two strips 35 and 40 play forwardly and rearwardly in the slot 42 as the door 10 is opened and closed. This slot 42 is of a vertical dimension suitable to permit free sliding passage therethrough of a cross-section of the welded or abutting areas of the strips 35 and 40, and of a horizontal dimension suitable to permit the angular shifting of the strips 35 and 40 on the bolt 36 as they travel through the slot 42 when the door 10 is opened and closed, Figure 4. These dimensions are clearly indicated in Figures 4 and 5. The position of the strips 35 and 40 relative to the slot 42, when the door 10 is fully open, is clearly shown in Figure 6. It will be noted that when the door 10 is fully opened the hook formation of the metal strip 35 is disposed contiguously rearwardly of the rear face of the leg 47 of angle plate 45 and that, when the door 10 is closed, as clearly shown in Figure 5, the rear ends of the strips 35 and 40 extend a substantial distance rearwardly of the angle plate 45.

The tendency of the spring steel strip 40 is to remain in the horizontal planes shown in Figure 5, and it is in this position when the door 10 is closed. However, as the door 10 is opened and the divergent zone 41 of the strips 35 and 40 passes through the slot 42, the rigid strip 35 causes the spring strip 40 to be moved upwardly and drag on the upper wall of the slot 42. The lower face of the rigid strip 35 also drags on the lower wall of the slot 42, and this dragging action of the two strips 35 and 40 increases in intensity until the low point of the lower face of the strip 35 opposed to the notch 38 reaches the slot 42. A further opening movement of the door 10 results in an easing up of the tension on the strips 35 and 40, due to the converging nature of the terminal part of the rigid strip 35, and the hook 39 then abuts the bracket flange 47 and limits the door opening movement. The effect of the sudden easing of dragging tension is to snap the door 10 into a locked opened position. In this open position of the door the terminal portion 44 of the free end of the spring steel strip 40 is bent slightly downwardly. The notched section 38 of the rigid strip 35 is a material aid in preventing the accidental swinging of the door 10 from opened position toward closed position, by reason of wind pressure or other fortuitous circumstances, inasmuch as some substantial closing force must be applied to the door 10 to overcome the intense dragging on the slot walls of the strips 35 and 40 when the trough-like area 38 is caused to pass through the slot 42.

As herein before stated, the forward edge 14 of the outer door panel 11 of the upper and lower door hinge bracket assemblies interiorly laps the forward part 3 of the body 1, and the bracket assemblies are disposed rearwardly of this lapping area. Therefore, a space 43 is provided around and forwardly of the axis of the hinges 8 and 9, which space 43 extends from the top to the bottom of the door 10, and within which the bracket assemblies and the forward terminal lapping edge 14 of the door 10 may play during the opening and closing movements of the door 10, as will be clearly seen in Figures 2 and 4.

What I claim is:

1. In a door holder for a structure having two relatively angular walls, a hinge formation, and a door 15 swingingly mounted by the hinge formation on one of the walls, the door comprising spaced exterior and interior panels, the interior panel having a terminal flange secured to the inner face of the exterior panel, the combination of a bracket secured to the other wall, a strengthening member secured to the interior door panel, and a holder arm pivotally secured to the strengthening member and movably supported by the bracket, the strengthening member having a portion thereof abutting the swinging edge of the door which is of channel formation, the hinge formation being secured in the channel formation.

2. A door holder, characterized as in claim 1, in which the bracket is slotted for movable support therein 20 of the holder arm, and in which a portion of the strengthening member is stamped out to form an ear 25 thereon for pivotal securing of the holder arm.

3. In a door holder for a door hinged on a frame, said holder comprising an arm pivotally connectable at one 30 end thereof to the door at a point spaced from the door hinge and a slotted bracket securable to the frame, said arm comprising superimposed rigid and spring steel strips relatively immovably secured together adjacent one end, the rigid strip being bent and said strips diverging continuously from said secured portions thereof toward their opposite ends, said secured portions of the strips 35 passing freely through the bracket slot, the arm having an overall slot-wall engaging dimension in its divergent zone greater than the depth of the bracket slot, said 40 strips when said overall dimension is passing through 45 the slot dragging on opposed walls of the slot thereby forming a flexible door catch.

4. A door holder, characterized as in claim 3, in which the arm is formed beyond the diverging zone with 50 a hook adapted to abut the bracket and limit the opening movement of the door.

5. A door holder, characterized as in claim 3, in which the strips are extended in converging relation 55 beyond the diverging zone and in which the extension of the rigid strip is provided with a terminal hook formed to abut the bracket and limit the opening movement of the door.

6. A door holder, characterized as in claim 5, in which the terminal portion of the extension of the spring 60 steel strip is slightly curved away from the opposed portion of the rigid strip extension.

7. A door holder, characterized as in claim 3, in which the strips are extended in sharply converging relation beyond the diverging zone for snap action of 65 the arm into position in the bracket slot, and in which means are provided limiting the opening movement of the door to such position.
